2 Claims. (Cl. 102—28)

It is a well known fact that, with electric spark detonators, one of the main difficulties consists in providing the optimum gap between electrodes. This gap is comparatively very small, so that in the present state of advance of the technology, it is so hard to calibrate this gap with a high degree of precision, that this difficulty hampers and slows down the production of such electric detonators, frequently introduces an insecurity factor and is certainly one of the conditions which justify a comparatively high cost price.

The electric detonators according to the present invention are essentially characterized by the fact that between both electrodes a thin layer of some electric insulating material is inserted, which is essentially characterized by the fact that there is at least one hole going right through this material and that this hole is disposed in the vicinity of the junction between one of the electrodes and an inflammable or explosive material.

The insertion of such a thickness of an insulating material right through which a free passage is provided leads to a simple, economic and accurate solution to the problem of exactly satisfying the distance condition between electrodes. The exact position of aforesaid passage is such that the spark which is produced at the proper time between electrodes reaches for certain the combustible or explosive material.

This extremely simple and original means can be applied under many different forms in order to make it adaptable to all practical cases.

It is therefore merely by way of example and without implying any kind of restriction, that some forms of embodiment are described in greater detail below, with reference to the appended drawings, of which:

FIGURE 1 is a diagrammatic radial cross-section of the essential elements which are part of an electric spark detonator according to the present invention;

FIGURE 2 is a cross-section by a plane whose trace follows the straight line II—II of FIGURE 1;

FIGURE 3 illustrates in radial cross-section the essential elements of the invention in an application which is decidedly different from the preceding one;

FIGURE 4 is a cross-section by a plane whose trace follows the straight line IV—IV of FIGURE 3;

FIGURE 5 illustrates in a radial cross-section a practical application of the design according to FIGURE 1;

FIGURE 6 is a cross-section by a plane whose trace follows the straight line VI—VI of FIGURE 5.

In the diagrammatic illustration of FIGURES 1 and 2, an electrode 1 of an electric detonator for projectiles is separated from the mass 2 by an insulating material 3. This electrode 1 lies on top of a priming mixture 4 surrounded by the second electrode 5 which is in contact with aforesaid mass 2. Aforesaid priming mass 4 lies in turn on top of the secondary charges 6. Aforesaid priming mixture 4 may be either conducting or not. If it is conducting, the detonator will have a lesser electric resistance and therefore a higher sensitivity. If on the contrary, aforesaid priming mixture is nonconducting,

2

the electrical resistance of the detonator will be practically infinite and its sensitivity considerably less.

In accordance with the main characteristic of the present invention, at least one thickness 7 of some insulating material such as for instance paper or mica or some synthetic resin or other is inserted between the first electrode 1 and its insulating wrapping 3 on the one hand, and the second electrode 5 and its priming load 4 on the other hand. At least one hole 8 goes right through this thickness 7 and is disposed in the vicinity not only of both electrodes 1—5 but also of the priming load 4. In the example which is illustrated diagrammatically, aforesaid channel 8 slightly overlaps the junction between the priming mass 4 and the second electrode 5 whilst having on top the corresponding part of the first electrode 1 and the insulating mass 3. The dimension of the thickness 7 determines systematically, without any difficulty whatever and with a high degree of precision that of the interelectrode gap 1—5. On the other hand, the manufacturing of such an electric detonator is extremely easy, fast and cheap. When the electrodes 1—5 are connected into circuit, the spark that flashes between them must necessarily reach the primary priming mixture 4.

The shape, the dimensions, the number of channels 8 vary according to the intended applications, which conveys to this new means a considerable universality, and to the electric detonator, a very high degree of fidelity.

The channel or channels 8 can be made either before or after mounting the detonator.

In the example illustrated in FIGURES 3 and 4, a very summary and diagrammatic illustration has been given of a form of embodiment based exactly on the same fundamental design but of very different morphology in order to show the universal character of the invention.

It shows again the first electrode 1', the second electrode 5', the insulating insert 7', the channel or channels 8' which go right through aforesaid insert and the primary priming mixture 4'. Also, in this same form of embodiment, the channel or channels are disposed in the vicinity of the two electrodes 1'—5' and of the primary priming mixture 4'. If, in the first example illustrated in FIGURES 1 and 2, the insert 7' assumed to shape of a very thin disc, in the example of FIGURES 3 and 4, it is coiled up cylindrically.

In this way it becomes possible to adapt the object of the present invention to any kind of electric detonator.

Finally, by way of simple information, FIGURES 5 and 6 illustrate a practical application of aforesaid electric detonator to a primary device for projectiles. In this case, we recognise again the first electrode 1'', the outer wrapping 2'' forming the mass of the detonator, the primary priming mixture 4'', the second electrode 5'', the secondary charges 6''—6', the insulating insert 7'' with its channels 8'', which latter in this case are two diametrically opposite openings.

For the ease of manufacturing, the two electrodes 1''—5'', the insulator 3'', the primary priming charge 4'' and the inserts 7''—8'' are mutually held together by a jacket 9'' adjusted in the outer jacket 2'' which forms the mass.

The object of the invention is to provide the means as such, consisting in establishing with precision the interelectrode gap by means of at least one insert of an insulating material pierced right through, at least in one spot, by a channel disposed in the vicinity both of the two electrodes and of the primary priming charge, as well as all and sundry applications of this means.

RICHARD M. WOOD, Primary Examiner.

VOLODYMYR Y. MAYEWSKY, Examiner.

What I claim is:

1. Electric spark detonator, comprising a priming mass, a first ring-shaped electrode surrounding said mass, a second cylindrical electrode located above said priming mass and a disc-shaped layer of an electrically insulating material having at least one hole, said layer being interposed between one of said electrodes and said priming mass, on the one hand, and the other of said electrodes, on the other hand, whereby said hole establishes a path for a spark between an edge of one of said electrodes and the other of said electrodes through said priming mass.

2. Electric spark detonator according to claim 1, wherein said second electrode is embedded in a mass of an electrically insulating material.
